TAG-FEEDING AND FORMING MACHINE

Charles G. Mortimer, Glen Ridge, N. J., assignor
to Joseph H. Lynch, Asbury Park, N. J.Original application June 19, 1931, Serial No.
545,424, now Patent No. 1,969,898, dated August
14, 1934. Divided and this application July 27,
1932, Serial No. 625,165.

5 Claims. (Cl. 153—2)

The object of the present invention is a machine for feeding and forming tags, especially tags for marking laundry, and as here shown it forms part of a machine which forms tags from a continuous ribbon of suitable material, makes suitable identifying marks thereon and applies the tag to the articles to be identified, a machine having these general objects being the subject of my application for patent filed June 10, 1931, Serial No. 545,424, Patent No. 1,969,898, dated August 14, 1934, of which the present application is a division.

The present invention comprises means for feeding the ribbon, means for severing a part 15 to form a tag, means for forming the tag and means cooperating therewith for carrying the tag therefrom, so as to make way for the next ribbon feeding operation, such carrying means being, as shown, adapted to hold the tag and carry it to points where it may be subjected to further operations. The invention further comprises other related improvements which will be first described with reference to the accompanying drawings and then pointed out in the claims. 20 While illustrated as a part of a complete machine of the character described in my aforementioned application, it is not intended that the invention as herein set forth and claimed is limited to that use, for it is susceptible of a wider application.

In said drawings—

Figure 1 is a rear view partly broken away of a machine for the forming, marking and applying of tags to articles, for instance pieces of laundry, to which, by way of illustration, the present invention is applied.

Figure 2 is a cross-sectional view partly broken away of the same, taken on the line 2—2, Figure 1, in the direction indicated by the arrows.

Figure 3 is an elevation of the cutting and forming punch and die and their operating mechanism, taken from the right side of the machine illustrated in Figure 1; the dies are shown open.

Figure 4 is a similar view taken in the same direction as Figure 2; the dies are shown closed.

Figure 5 is a partially sectional plan view of the dies, taken on the line 5—5, Figure 4, in a direction indicated by the arrows, the dies being open.

Figure 6 is a sectional view taken on the line 6—6, Figure 4, in the direction indicated by the arrows.

Figures 7, 8 and 9 are side views of the contiguous parts of the punch and die, respectively

in open, partly closed, and completely closed position.

Figure 10 shows the ribbon and the line of severing of a tag therefrom, as caused when the punch and die are in the position shown in Figure 8.

Figure 11 shows the tag completed by the closing of the punch and die, as illustrated in Figure 9, the tag being now in condition to receive identifying marks.

Figure 12 is a detail view looking from the left of Figure 1 illustrating means of operating the gripping fingers.

Figure 13 is a detail rear elevation of said mechanism, partly in section.

Figure 14 is a sectional view, taken in the opposite direction to that used in Figure 12, of other portions of said mechanism, the plane of section being indicated by the line 14—14, Figure 13.

Figure 15 is a view of part of the mechanism shown in Figure 13 illustrating the means for retracting the gripping fingers.

Figure 16 is a view showing the gripping fingers open, and

Figure 17 is a view of the end of the upper gripping finger.

A considerable part of a complete machine for forming, marking and affixing tags to pieces of laundry is illustrated, for further description of which reference may be had to my original application of which this is a division. The present description will be confined to so much thereof as directly cooperates with the mechanism for feeding, forming and removing a tag, which forms the subject of the present application.

1 is the metal ribbon from which the tags are made. The metal ribbon comes from a magazine roll of conventional design, not shown. This ribbon is provided with perforations distributed as per Figure 10, the mechanical purpose of which will be apparent when the individual operations are described. Besides these mechanical reasons for providing such perforations, I

provide these apertures to allow a free flow of water through the tags and through that part of the laundry pieces to which the tags are applied, and around which they are folded, as described in my original application. This secures a thorough contact of the working liquid and the laundry pieces also in the neighborhood of and between the folds of the tag. The ribbon runs over an idler 2, which acts as a guide and secures the contact of the ribbon with the feed roll 3

over a long part of its circumference, and also secures engagement with more than one pair of the propelling pins 4 on the feed roller. These pins engage with the outermost perforations 5 on both sides of the ribbon.

From this feed roller the ribbon is forced through straightening rolls 6, 7 and 8, more clearly shown on Figures 2, 3 and 4. Roll 6 can be adjusted with respect to its distance from the pair of rollers 7 and 8. This is done by adjustment screw 9. When a new ribbon is inserted, it is convenient to be in a position to increase this clearance.

After leaving the straightening rolls, the ribbon enters the die device 10 through slot 11 acting as a guide. This is as far as the ribbon goes when a new ribbon is inserted.

An electric circuit including a starting button 13 and suitable intermediate mechanism is employed to couple the drive wheel 33 with the operating shaft 36, which coupling is automatically disengaged when the shaft 36 has completed a revolution, and the shaft 36 is connected by eccentric 54, rod 55a and crank 56 to the oscillating member of a one-way ratchet-toothed clutch 61 on shaft 59, as more fully described in my original application, so that during a part of each revolution of shaft 36, the feed roller 3 is turned sufficiently to feed the ribbon the length of one tag.

At the end of shaft 59, a bevel gear 65 is keyed, which drives the intermediate bevel member 66, 66a, shown on Figures 1 and 2. This member is supported by support 67 and drives the bevel gear 68. Bevel gear 68 runs loosely on shaft 36, by which it is supported. An axial movement of 68 may be prevented by suitable collars on the shaft, not shown. The bevel gear 68 carries three arms 69 which are equally spaced around its circumference.

It will be apparent from Figure 13 that these arms carry each a pair of gripping fingers 70 and 71. The gripping fingers are connected to the arm 69 by connecting lever arms 72 which are rotatable around pin 73. The lever arms 72 each carries a toe 74 which rests on a pin-head 75 of pins 76. A definite engagement of the toes with the pin-heads is secured by springs 77. A movement of the pins 76, on Figure 13, to the right causes a movement of the lever arms and the gripping fingers in the plane of the centerline of shaft 36. The gripping fingers 70 and 71 are adapted to hold one tag and transport it to the positions where the individual operations of making, identifying and applying the tag take place. These positions will be henceforth called "stations". Station I is the station where the tag is cut and shaped; at station II the identification marks are applied to the tag; at station III the tag is applied to the material to be identified.

The gripping fingers are shown in Figures 16 and 17. Finger 70 carries pins 78 which are spaced apart so that they fit into the holes 5 of the ribbon, indicated by lead lines at the left 65 of the ribbon on Figure 10. The gripping finger 71 has holes 78a corresponding to the pins 78 so that when the two fingers are in closed position, the tag is accurately secured in proper position. The fingers 70 and 71 are kept in closed position by the spring 79. Finger 70, however, has an extension which carries a contact roller 80. Whenever this contact roller rolls over a cam-like surface of suitable shape, the fingers are opened. The fingers are geared together, as

shown, by teeth 81 so that both take part in this opening motion.

After the ribbon is fed into the machine, as previously described, straightened out, and put into the guide slot 11, the machine will be started by pressing the starting button. At each operation of the starting button, the ribbon will proceed for the length of one tag further into the machine, and will at, for instance, the third operation, be sufficiently advanced so that a complete tag can be cut by the die members 82 and 99, shown in Figures 3 to 9.

During the operation of the last feed motion which takes place, as aforesaid, during the second and third quarter of the turn of the main shaft 15 36, the arm 72 approaching the die is held in a swung-out position so as to keep clear of the die. This is accomplished by a stationary track 83a against which the pin 76 abuts. On passing beyond track 83a, the pin 76 releases the arm 72 to the action of spring 77, which throws the gripping fingers into the opening provided for them in the dies 82 and 99 just before or after the gripping fingers are opened preparatory to gripping the ribbon.

Just before the die members 82 and 99 are closed, the contact roll 80 runs up on a shoe 91, shown on Figure 12, which causes the fingers 70 and 71 to open. The shoe 91 is attached to the shoe holder 92 which is pivoted at 93 to the stationary support 94. The shoe holder 92 has an extension provided with a cam follower 95 which normally rides on cam plate 96 which holds cams 97 and 98. Cam plate 96 is keyed to shaft 36. The shoe 91 is forced outwardly with regard to 35 the shaft 36 as long as 95 rides on 97, and by this outward movement, the fingers 70 and 71 are kept open until the cam plate 96 has revolved far enough to allow cam follower 95 to drop down from the cam 97. At this moment, the fingers are 40 closed. The positions of the shoe 91 and cam 97 are so timed with respect to the operation of the die members 82 and 99, that this closing of the fingers and gripping of the ribbon takes place just before the die closes in order to cut and 45 shape a tag.

Figures 3 to 9 show the die in detail. The die consists of two members 82 and 99 dove-tailed in a guide groove in die block 111. Figure 7 shows the die in full open position with the ribbon inserted ready to be cut and shaped. The face of the male die 82 has a projecting part 82a to enter a depression 99a in the face of the female die 99. At the edge of the depression 99a toward the ribbon guide 11, and forming a downward extension of the body of the die 99 to which it is fastened, is a female cutting member 104 with which cooperates the male cutting member 100, mounted by spring plunger 100a on die member 82 so that it is adjacent to the projecting part 82a of member 82 and normally above the surface of such part as shown in Figure 7. The cutter members 100 and 104 are serrated so as to intermesh on their meeting faces. When the dies are brought together, in a manner to be presently explained, until they reach the position shown in Figure 8, the tag is first cut from the ribbon, as shown in Figure 10, and the male cutter carries the tag edge into contact with the face of the die member 99 and holds it there, as 60 shown in Figure 8, while the die members continue to approach, the male cutter 100 receding against the resistance of spring plunger 100a as the male portion of die member 82 enters the depression of die member 99, causing the tag to 65 70 75 80 85 90 95 100 105 110 115 120 125 130 135 140 9315 9320 9325 9330 9335 9340 9345 9350 9355 9360 9365 9370 9375 9380 9385 9390 9395 9400 9405 9410 9415 9420 9425 9430 9435 9440 9445 94

be bent downward on transverse lines adjacent to its serrated edges. At the same time, grooves 101, 102 and 103 on die member 99, coacting with corresponding ridges on the face of die member 82,

- 5 raise reenforcing ribs 101a, 102a, 103a on the tag and the tag is thus cut off and shaped, as shown in Figure 11, as the dies reach the position shown in Figure 9. The openings 105 on the die 99 and 106 on the punch 82 are to accommodate the 10 gripping fingers 70 and 71, which enter therein, as already described, when the jaws of the die are in the open position shown in Figure 7.

Figures 3, 4, and 5 show the operation of the die. On shaft 36 is keyed a cam plate 107 carrying cam 108. Upon turning the shaft 36, this cam moves cam follower 109 at the end of arm 115, which is mounted on disc member 110. This disc member 110 rotates freely in a recess of die-block 111 and is held within this recess by the ring member 112. The disc 110 is provided with two eccentric slots. The die member 82 carries pin 113 and the die member 99, the pin 114, each occupying one of said slots. It is obvious that upon revolving of shaft 36 in the direction indicated by the arrow, Figure 3, the connecting arm 115 is turned and the die members 82 and 99 will be drawn together. As soon as the cam follower 109 rides over the cam 108, the die members 82 and 99 will be pulled apart by means of spring member 116a (which is fastened on one end to the die-block 111, and on the other end to the arm 115), and the die is ready again to receive the ribbon. The die block has a gate or channel 111a to permit the passage of gripping fingers and tag carried thereby.

The finishing of the tag within the die was the last action brought about during the first 90° of the turn of shaft 36. Upon completion of this 90° turn, the previously mentioned ratchet coupling 58 and 57 is engaged and further ribbon is brought into the machine by the revolution of feed roller 3. While the shaft 36 continues to revolve for 180°, the transport arms 72 with gripping fingers 70 and 71 are moved 120°. By

this movement the tag which has been just finished in the die is carried to the station II where the identification marks will be embossed on it.

I claim:—

1. In a machine of the character described, the combination of means for feeding a ribbon intermittently the length of a tag to be severed therefrom, a supporting block, punch and die mechanism supported thereon having means for severing and for forming the severed tag, means for operating the punch and die mechanism alternately with the operation of the ribbon-feeding mechanism, means for gripping the tag and means operative when the punch and die mechanism is 10 open for moving the gripping means and tag carried thereby therefrom.

2. Mechanism as set forth in claim 1 in which the punch and die mechanism has passages in the meeting faces of the punch and die to permit the 20 entry of the gripping means.

3. Mechanism as set forth in claim 1 in which the punch and die supporting block has a gate in line with the meeting faces of the punch and die to permit passage of the gripping means and tag. 25

4. In mechanism of the character described, the combination of intermittently operated ribbon feed mechanism, punch and die means for severing a tag from the ribbon, and bending its ends, and means for gripping and removing the formed 30 tag from the punch and die.

5. In a machine of the character described, the combination of reciprocable die members having corresponding male and female parts for bending a tag, a female cutting member on one die member 35 and a male cutting member resiliently mounted on the other die member, the cutting members being associated with the male and female parts of the respective die members to cut a tag from the tag ribbon immediately in advance of the 40 bending of the tag by the male and female parts of the die members.

CHARLES G. MORTIMER.
